UNITED STATES PATENT OFFICE.

ALPHONSE IEHL, OF MAZAMET, FRANCE.

UMBRELLA OR PARASOL.

SPECIFICATION forming part of Letters Patent No. 257,872, dated May 16, 1882.

Application filed March 2, 1882. (No model.) Patented in France August 20, 1881; in England December 6, 1881; in Belgium December 23, 1881, and in Austria December 27, 1881.

To all whom it may concern:

Be it known that I, ALPHONSE IEHL, a citizen of the Republic of France, residing at Mazamet, France, have invented certain Improvements in Umbrellas and Parasols, of which the following is a specification.

This invention relates to a combination-lock for the runner of an umbrella or parasol, whereby the latter may be locked fast when the umbrella is closed, and the cover cannot then be distended until the runner is unlocked by one who holds the combination.

The novel features of the invention will be fully set forth in the claims.

15 In the drawings which serve to illustrate my invention, Figure 1 is a side elevation of a portion of the umbrella-stick bearing the runner and its lock, and showing the former locked fast. Fig. 2 is a similar elevation, showing 20 the runner unlocked. The remaining figures illustrate the lock. Figs. 3 and 4 are horizontal sections of the lock, the former showing it unlocked and the latter locked. Fig. 5 is a vertical section taken on line M N in Fig. 3.

25 Figs. 6 and 7 are vertical sections, both taken on line P. Q in Fig. 3, the former showing the lock unlocked and the latter showing it locked. M' is the stick of the umbrella, and E is the runner to which the cover-braces are hinged.

30 The runner is provided with a bead or flange, t, to rest on the lock when the umbrella is closed, and two locking-catches, g g, as shown in Fig. 2.

The lock is constructed as follows: D is a 35 tube, which is secured to the stick by a pin, screw, or rivet, a, or in some other permanent manner. This tube is large enough for the lower end of the runner to enter it freely. On the upper end of this tube is fixed a ring, B,

40 the outer periphery of which is divided into spaces, in which are impressed or marked distinctive figures, as the numerals 1, 2, 3, &c., as shown in Figs. 1 and 2. Below, on the tube D, is formed a shoulder, C, above which screw-threads are formed on the tube, and on the tube at this point is screwed a collar, F. Between the fixed ring B and the screw-collar F are arranged two rings, A A, which resemble the ring B, and are correspondingly marked 45 with numerals 1, 2, 3, &c. These rings turn

freely on the tube D, but may be clamped against the fixed ring B by screwing the collar F up against them. The rings A A are hollowed or channeled on the inside, so as to give them a U-shaped section, and the lips or flanges e e bear on the external surface of the tube D. The tube D has a vertical slot, c, formed in it, which opens out at the top, and from this slot branch short lateral slots b b, separated by projecting parts d d. The slots b are arranged opposite the channels in the rings A B, and the parts d opposite the flanges e on the rings. These flanges e are cut away on the fixed ring B, opposite the slot c in the tube D, and they are cut away at one point (c' 65 in Figs. 3 and 4) on the rings A, of the same width substantially as the said slot c, so that by turning both rings A the recesses c' in their flanges may be brought to coincide with the said slot c, as shown in Fig. 6, and thus leave 70 an open way for the passage of the locking-catches g g on the runner when the latter is drawn down into the lock.

To lock the runner in place it is, then, only necessary to turn one or both of the rings A a 75 little way around on the tube D, when the catches g will take under the interfering flanges e on the rings, and the runner cannot be moved.

To release the runner the recesses c' must again be brought to coincide with the slot c. 80 In order to enable the operator to do this I arrange that certain known figures or numerals on the rings A A and B are brought into line when said recesses coincide with the said slot— as, for example, in the present case, like numerals 85 on each and all, as shown in Fig. 2; but any combination may be employed, as will be well understood.

I will now explain the function of the lateral slots b. When the runner is brought down 90 to close the umbrella it is customary to employ a spring to hold it in place. I discard this spring and arrange the lock on the stick in such a manner with respect to the position of the runner that when the latter is drawn down the 95 locking-catches g will not normally enter the slot c, but stand a little to one side—that is to say, toward that side where the slots b are formed. Then, in bringing down the runner, it is only necessary to turn or twist it a little on 100

the stick—which the elasticity of the ribs and braces will always permit—until the catches *g* will enter and pass down the slot *c*, when the reactionary force exerted by the runner in seeking to resume its normal position will cause the catches to enter the slots *b* and take under the parts *d* between said slots. To release the runner and bring the catches back into the slot *c*, the runner must be again turned slightly on the stick.

Where it is not necessary to employ the lock, or where the owner of the umbrella desires to use it, the rings *A A* may be set as in Figs. 2 and 5, and clamped fast in that position by means of the screw-collar *F*, as before stated.

One or more rings *A A* may be employed, more than one movable ring being desirable only in order to increase the complexity of the lock and the number of combinations.

I am aware that combination and permutation locks having lettered and numbered rings are common, and that locks of this character have been fixed on the runners of umbrellas for locking them fast when the cover of the umbrella is collapsed; but my arrangement of the lock fixed to the stick of the umbrella and its arrangement to serve a double purpose—that is to say, to serve as a permutation-lock for the runner and as a temporary holdfast for the same, as herein described—has not been known before, so far as I am aware.

Having thus described my invention, I claim—

1. The combination, with the stick of an umbrella or parasol, of a runner provided with a

catch, *g*, a tube, *D*, mounted on and fixed to the stick and provided with a fixed ring, *B*, a vertical slot, *c*, and a lateral slot, *b*, and a loose ring, *A*, mounted to turn on the tube *D*, and provided with recessed flanges *e e*, and with characters on its outer periphery arranged to be brought into coincidence with similar characters on the fixed ring *B*, all arranged substantially as set forth.

2. The combination, with the stick of an umbrella or parasol, of a runner provided with a catch, *g*, a tube, *D*, provided with a vertical slot, *c*, and lateral slot *b*, and a fixed ring, *B*, and a loose ring, *A*, mounted to turn on the tube *D*, and provided with characters on its outer periphery adapted to be brought into coincidence with similar characters on the ring *B*, the tube *D* being fixed on the stick with the entrance of the slot *c* a little to one side of the path of the catch on the runner, whereby it is necessary to twist the runner on the stick in order to cause the catch to enter the slot, substantially as and for the purposes set forth.

3. The combination, with the stick of an umbrella or parasol, of the slotted tube *D*, provided with the fixed ring *B* of the loose ring *A*, and the screw-collar *F*, all constructed and arranged to operate substantially as set forth.

In witness whereof I have hereunto signed my name in the presence of two subscribing witnesses.

ALPHONSE IEHL.
